SAFETY CLOTHESPIN

Gustave D. Kunkel, Bridgeport, Conn.

Application August 31, 1945, Serial No. 613,725

7 Claims. (Cl. 24—137)

1

This invention relates to clothespins.

An object of the invention is to provide an improved clothespin of simple and economical construction, which is extremely easy to apply and which holds the clothes on the line with considerable tenacity so that there is obviated the dropping of clothes and consequent soiling thereof.

Another object of the invention is to provide a clothespin having the above characteristics, which is more rugged and resistant to splitting or breakage during use, and which may not be easily inadvertently dismantled.

A feature of the invention is the provision of a clothespin having the above advantages, which while gripping the clothes firmly, operates so as to cause less abrasion and wear to the clothes.

Another feature of the invention is the provision of a clothespin having a number of components or parts so arranged that those not required to be accessible are enclosed, out of view and protected.

These and other objects and features are attained, as illustrated in the embodiment of the invention described herein, by a novel structure comprising an elongate body and finger-operable sleeve slidably mounted thereon, one end portion of the latter and a side portion of the body having cooperable hook-shaped jaws arranged to clamp between them both the line and the clothes which are folded over the latter. The sliding of the sleeve on the body, to open the jaws for applying or removing the clothespin may be easily accomplished entirely by the hand in which the pin is held, and the clamping action of the jaws is of a character which successfully resists opening pressures due, for instance, to wind blowing the clothes, or to pulling on the clothes from other causes. The clothespin does not rely for its clamping pressure upon the resiliency of a one-piece wooden structure which suffers cross-grain tension when in use and therefore often splits; instead the clamping pressure is obtained by use of a metal compression spring carried within the body and sleeve and concealed thereby, and the working stresses of the latter two parts are such that, even if these be made of wood there is no possibility of their structural failure and consequent breakage of the clothespin, and therefore no possibility of the pin failing to hold the clothes to the line.

In applying the clothespin of the present invention to clothes on a line, the jaws of the pin are spread widely so that they may be placed over the line and fold of the clothing without rubbing

2

or friction. When the clothespin is released, the jaws come together and clamp the folded cloth to the line without abrasion or wear, in contradistinction to the wedging type of action commonly employed in clothespins, where the surface of the cloth is subjected to an abrading action which causes unnecessary wear.

Other features and advantages will hereinafter appear.

10. In the accompanying drawings:

Figure 1 is a side elevational view of the clothespin of this invention, the parts being in closed or clamping position.

Fig. 2 is a similar view but with the parts held 15 in open position, preparatory to applying the clothespin to clothes on a line.

Fig. 3 is a longitudinal vertical section of the clothespin, clamping a cloth to a clothesline, and

Fig. 4 is a transverse section on the line 4—4 20 of Fig. 3.

The clothespin shown, illustrating a preferred embodiment of the invention, comprises an elongate cylindrical body 10 having a longitudinal circular bore 11 extending from one end 10a thereof to a point adjacent the opposite end 10b. The body 10 is provided with an elongate cut 12 having a depth approximately equal to the radius of the body, so that the flat longitudinal walls 12a of the cut lie substantially in a diametric plane of the body, as shown in Fig. 4. At one end of the cut 12 the body has a flat transverse shoulder 13, and at the other end of the cut, the body is shaped to provide a hook 14 adapted to function as a clamping jaw. Preferably the radius of the hook 14 is approximately equal to, or slightly larger than that of a standard rope clothesline.

For cooperation with the jaw 14, and for convenient manipulation by the finger of a hand, there is provided a clamping sleeve 15 of circular tubular shape, closely fitting and slidable on the exterior of the body 10. One end of the sleeve 15 is cut away to provide a hook-shaped jaw 15a adapted to cooperate with the jaw 14 of the body 10 for clamping purposes.

As shown in Fig. 3, the jaws 14 and 15a may be brought together by sliding the sleeve 15 along the body 10, and may be made to clamp a cloth 16 folded over a clothesline 17.

50. For the purpose of providing yieldable clamping pressures between the jaws 14 and 15a, the sleeve 15 is spring-urged toward a limiting position as shown in Fig. 1, nearest the left end 10b of the body 10. To accomplish this, a helical compression spring 18 is located within the bore

11 of the body 10, one end of the spring engaging a plug 19 press-fitted in the end 10a of the body, and the other end engaging a plunger 20 slidable in the bore 11. The plunger 20 engages one end of a semi-cylindrical lug or abutment 21 located within the bore of the sleeve 15, the said lug being secured to the sleeve by a driven pin 22. Preferably the other end 21a of the lug 21 is concave shaped as shown to conform to the hook-like contour of the lower end of the jaw 15a of the sleeve 15.

Thus it will be seen that, due to the compression of the spring 18, the plunger 20, lug 21 and sleeve 15 will be continually urged toward the left end 10b of the body 10, bringing the jaws 14 and 15a together for clamping purposes. The sleeve 15 is prevented from passing beyond the extended left position shown in Fig. 1 by engagement of the jaw 14 with the lug 21. Similarly, the sleeve 15 is prevented from passing beyond the fully retracted position shown in Fig. 2 by engagement of the lug 21 with the shoulder 13 of the body 10 which forms a stop therefor.

Preferably the exterior of the sleeve 15 is provided at the sleeve ends, with portions 15b and 15c of enlarged diameter to enable the fingers of a user's hand to readily grip the sleeve for retracting the same. The retracting operation may be conveniently carried out by the fingers of the hand which supports or holds the clothespin, in the following manner. The end 10a of the clothespin body may be placed against the palm of the hand, near the center. The thumb and forefinger of the hand may then grasp between them the enlarged portion 15b of the sleeve 15, and the latter may be moved to the retracted position shown in Fig. 2 by bending these fingers to shorten their effective length, thereby compressing the spring 18, separating the jaws 14 and 15a and enabling the clothespin to be readily placed in position for clamping a cloth on a line. Upon releasing the thumb and forefinger, the sleeve 15 will snap back under the urging of the spring 18, causing the jaws 14 and 15a to clamp the cloth 16 and line 17 as shown in Fig. 3.

Another method of conveniently retracting the sleeve 15 while holding the clothespin in one hand is to place the end 10a of the body against the web-like junction of the thumb and forefinger, adjacent the palm, and grasp the enlarged portion 15c of the sleeve between the thumb, fore and middle fingers in the manner one grasps a pen or pencil. The fingers may then be flexed to easily and quickly retract the sleeve 15.

If desired, the exterior surface of the sleeve 15 may be knurled to provide for a non-slipping surface. The body 10, sleeve 15, plug 19, plunger 20 and lug 21 may be all advantageously made of wood. Or they may be made of suitable plastic material, or of metal, as desired.

Other methods of fastening the plug 19 and lug 21 to the body 10 and sleeve 15 respectively may be employed. These parts may be cemented together, or welded, soldered, or otherwise joined.

Preferably the bore 11 of the body 10, at its innermost end 11a extends beyond the hook-shaped end or jaw 14 of the cut 12 thereby providing a recess in the jaw which facilitates its holding properties.

When the clothespin is clamping a cloth 16 to a clothesline 17 as shown in Fig. 3, a positive gripping action is obtained under the urging of the spring 18, due to the substantially complete encirclement of the line by the jaws 14 and 15a. It will be seen that by this encirclement the like-

lihood of the line 17 and cloth 16 slipping out of the grasp of the jaws is extremely remote, even though strong pulls are exerted on the cloth. Therefore, by use of the present improved clothespin, there is obviated the pulling of clothes from the line by the wind, for example, with the consequent soilage and necessity for rewashing or recleaning.

Because of the one hand manipulation, when hanging clothes on a line the cloth may be wrapped around the line with one hand and the clothespin opened and applied with the other hand.

An alternative method of applying the clothespin after the cloth has been wrapped around the line would be to grasp the end portion 10a of the body firmly in the hand, apply the clothespin to the cloth and line at the point indicated by the numeral 23 in Fig. 1, and press the sleeve 15 back to retracted position by pressure against the same by the cloth and line. It will be found that, by such a procedure the cloth 16 and line 17 will snap in between the jaws 14 and 15a and be securely held thereby, all without first touching or drawing back the sleeve 15 with the fingers. The clothespin as thus constructed presents a neat and attractive appearance due to the spring 18, plug 19, plunger 20 and lug 21 being completely enclosed, and this construction prevents tampering with these parts, or inadvertent interference with their functioning, and protects the spring 18 from the elements and other destructive instrumentalities. Also, there is no possibility of the parts springing out of place, to render the clothespin inoperative, since they are wholly confined.

Variations and modifications may be made within the scope of this invention and portions of the improvements may be used without others.

I claim:

1. A clothespin comprising an elongate body having a cut in one side, a portion of the body bordering said cut comprising a hook-shaped jaw; a sleeve encircling the body and slidably thereon, an end portion of said sleeve comprising a hook-shaped jaw cooperable with the jaw of the body for clamping clothes to a line; means on the body for yieldably urging the sleeve to a clamping position on the body wherein the jaws are brought together to clamp the line between them; and a stop on the body for limiting movement of the sleeve on the body in a direction separating the jaws.

2. A clothespin comprising an elongate hollow body having a cut in one side, a portion of the body bordering said cut comprising a hook-shaped jaw; a sleeve encircling the body and slidably thereon, an end portion of said sleeve comprising a hook-shaped jaw cooperable with the jaw of the body, each of said jaws having opposed clamping surfaces for clamping clothes to a line; means, including a compression spring carried within the hollow of the body, for yieldably urging the sleeve to a clamping position on the body wherein the clamping surfaces of the jaws are brought together to clamp the line between said surfaces; and a stop on the body for limiting movement of the sleeve on the body in a direction separating the jaws.

3. A clothespin comprising an elongate cylindrical body having a cut in one side extending longitudinally of the body, a portion of the latter at one end of the cut comprising a hook-shaped jaw; a sleeve encircling the body and slidably thereon, an end portion of said sleeve compris-

ing a hook-shaped jaw cooperable with the jaw of the body, each of said jaws having a clamping surface for clamping clothes to a line; a lug secured to the inside of the sleeve, extending into the cut of the body and engaging the walls of the cut for preventing rotative movement of the sleeve, said lug having a clamping face opposed to the jaw on the body; means engaging the lug for yieldably urging the sleeve to a clamping position on the body wherein the lug and jaws are brought together to clamp the line between them, said lug, by engagement with an end wall of the cut in the body, limiting longitudinal movement of the sleeve in a direction separating the jaws.

4. A clothespin comprising an elongate cylindrical longitudinally bored body having a cut in one side extending longitudinally of the body, a portion of the latter at one end of the cut comprising a hook-shaped jaw having a clamping surface; a sleeve encircling the body and slidable thereon, an end portion of said sleeve comprising a hook-shaped jaw having a clamping surface cooperable with the clamping surface on the jaw of the body for clamping clothes to a line; a lug secured to the inside of the sleeve, extending into the cut of the body and engaging the walls of the cut for preventing rotative movement of the sleeve; a compression spring located within the bore of the body, applying pressure to the lug and yieldably urging the sleeve to a clamping position on the body wherein the clamping surfaces of the jaws are brought together to clamp the line between them, said lug, by engagement with an end wall of the cut in the body, limiting longitudinal movement of the sleeve in a direction separating the jaws.

5. A clothespin comprising an elongate body having a cut in one side, a portion of the body bordering said cut comprising a hook-shaped jaw; a sleeve encircling the body and slidable thereon, an end portion of said sleeve comprising a hook-shaped jaw cooperable with the jaw of the body, each of said jaws having a clamping surface for engaging and clamping clothes to a line; means for yieldably urging the sleeve to a clamping position on the body wherein the jaws are brought together; and a stop on the body for limiting movement of the sleeve on the body in a direction separating the jaws, said sleeve, when in clamping position, covering and concealing the cut in the body at all points except where the line extends through the cut.

5 6. A clothespin comprising an elongate, cylindrical, longitudinally bored body having a substantially diametric cut in one side extending into the bore, and extending longitudinally of the body, a portion of the latter at one end of the cut comprising a hook-shaped jaw; a circular sleeve encircling the body and slidable thereon, an end portion of said sleeve comprising a hook-shaped jaw cooperable with the jaw of the body, said jaws having clamping surfaces for clamping clothes to a line; a semi-cylindrical lug secured to the inside of the sleeve, extending into the cut and engaging the surfaces thereof to prevent rotative movement of the sleeve on the body; a plunger closing the bore and slidable in the bore of the body for engaging the said lug; a plug fitted into the bore of the body at one end thereof; and a compression spring located in the bore of the body between the plug and the plunger, urging the latter and sleeve to yieldably maintain the jaws in clamping position, said lug of the sleeve, by engagement with an end wall of the cut in the body, limiting longitudinal movement of the sleeve in a direction separating the jaws.

15 7. A clothespin comprising an elongate body having a cut in one side, a portion of the body bordering said cut comprising a hook-shaped jaw; a clamping member including a sleeve encircling the body and slidable thereon, said member having a hook-shaped clamping surface opposed to and cooperable with the jaw of the body for clamping clothes to a line, said member having an enlarged diameter to provide a finger grip; means on the body for yieldably urging the member to a clamping position on the body wherein the jaws are brought together; and a stop on the body for limiting movement of the member on the body in a direction separating the jaws.
